Clifford Brooks Stevens, Milwaukee, Wis., as-
signor to Perfex Corporation, Milwaukee, Wis.,
a corporation of Wisconsin

Application September 5, 1939, Serial No. 87,046

Term of patent 7 years

To all whom it may concern:

Be it known that I, Clifford Brooks Stevens, a citizen of the United States and a resident of Milwaukee, in the county of Milwaukee and State of Wisconsin, have invented a new, original, and ornamental Design for an Air Conditioning Control, of which the following is a specification, reference being had to the accompanying drawing, forming a part thereof.

Figure 1 is a perspective view of an air conditioning control showing my new design;

Figure 2 is a side elevation thereof;
Figure 3 is a top plan view thereof;
Figure 4 is a front elevation thereof; while
Figure 5 is a bottom view.
I claim:
The ornamental design for an air conditioning control, substantially as shown.

CLIFFORD BROOKS STEVENS.
